CLAIM

The ornamental design for a photo-voltaic module, as shown and described.

DESCRIPTION

FIG. 1 is a perspective view of a photo-voltaic module showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and

FIG. 8 is a bottom plan view thereof; and,

FIG. 9 is an enlarged view of the encircled area 9 of FIG. 1. The equal-length broken lines depict portions of the photo-voltaic module that form no part of the claimed design. The dot-dot broken lines in FIG. 1 and FIG. 9 illustrate the boundaries of the enlarged view and form no part of the claimed design.
